CLAIM

The ornamental design for a device for showing elapsed time, as shown and described.

DESCRIPTION

FIG. 1 is a front perspective view of a device for showing elapsed time. The broken lines showing the numbers are for illustrative purposes only and form no part of the claimed design; and,

FIG. 2 is a front perspective view thereof similar to FIG. 1 with the numbers removed for clarity.

Any elements shown in broken lines form no part of the claimed invention in this application, and are instead included to show environmental aspects of the claimed invention.
